(57) **CLAIM**

We claim the ornamental design for a combined noodle cap and beverage holder, as shown and described.

DESCRIPTION

FIG. 1 is a perspective view of the combined noodle cap and beverage holder;

FIG. 2 is a bottom left side perspective view thereof;

FIG. 3 is a front elevation view thereof;

FIG. 4 is a back side elevation view thereof;

FIG. 5 is a top view thereof;

FIG. 6 is a bottom view thereof; and,

FIG. 7 is a bottom right side perspective view thereof.

The broken lines shown in the drawings are for illustrative purposes only and form no part of the claimed design.
